MULTICYLINDER BLOCK FOR AIR COOLED ENGINES

Charles S. Brown, Syracuse, N. Y.

Application April 4, 1934, Serial No. 718,973

4 Claims. (Cl. 123—171)

This invention relates to multi-cylinder blocks for air cooled engines, and has for its object a cylinder block having a passage, or passages, in the portion thereof between the cylinder bores so arranged as to compensate for distortion of the mass of metal between the bores, and differences in expansion throughout the whole block, and thus avoid misalignments and undue distortion of the bores as the cylinder block heats, and when casting.

It further has for its object, an arrangement of heat radiating fins, particularly along the sides of the block and the mass of metal between the bores, to quickly conduct the heat to the cooling air current, and an upright passage between the bores, which passage is preferably open at its ends to facilitate the cooling, and to prevent undue distortion of the mass of metal between the bores.

It further has for its object, a multi-cylinder air cooled block in which the cylinder bores are provided with sleeve liners embedded therein to form a good mechanical and thermal union between the liners and the body of the block, together with a passage between the bores in which portions of the peripheries of adjacent liners are exposed, the body of the block and its heat radiating flanges being of a metal having a greater heat conductivity than that of the sleeve, or liner.

Other objects appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a plan view of a multi-cylinder air cooled block embodying my invention.

Figure 2 is a sectional view on line 2—2, Figure 1.

Figure 3 is a sectional view on line 3—3, Figure 2.

Figures 4 and 5 are respectively a plan view, and an elevation, of one of the sleeve liners.

Figure 6 is a plan view, similar to Figure 4, of a slightly modified form of liner.

Figure 7 is a fragmentary, sectional view taken on line 7—7, Figure 6.

This multi-cylinder block for air cooled engines comprises generally, a body 1 formed with a plurality of cylinder bores 2, circumferentially extending heat radiating flanges 3, and a pas-

sage, or passages, 5 extending lengthwise of the bores between the same, said passage preferably being open at its upper and lower ends for the passage of air, and being so located as to allow expansion and contraction of the mass of metal between the bores without causing misalignment of the cylinder bores, and compensating for differences in expansion throughout the whole block and the liners. The passage 5 opens, at its upper end, into the surrounding air into space 10 between the cylinder heads, or through the hole in the head if the heads are a single block, in contradistinction to individual heads. The passage communicates, at its lower end, with the surrounding air through a transverse passage, or passages, 5^a in the block. The passages 5, 5^a permit the air to move, or circulate.

Preferably, the cylinder bores 2 are provided with sleeve liners 6, usually of a ferrous metal as cast iron, or steel, which is embedded in the body during the casting operation. The body is usually of aluminum, or of aluminum alloy, or of any other metal having greater heat conductivity than iron, or steel. The side portions 4 of the flanges, on the sides of the block and projecting from the mass or portion of the body which extends between the bores, are continuous of the end portions of the flanges, that is, the portions around the ends of the block. The outer faces of the side portions 4 of the flanges, and the mass of metal between the cylinder bores, curve inward slightly out of a straight line.

In order to form a good mechanical and thermal, or heat conducting union between the sleeve liners 6 and the body, the liners are provided with peripheral flanges 7 which are embedded in the body 1, and portions 8 of these liners with their flanges are exposed in the air passage 5. This air passage 5 is usually located between the cylinder bores where they are nearest together.

As seen in Figures 1 and 4, these sleeves or liners 6 are provided with flanges 9 at their upper or head ends which lap the head ends of the block around the bores, and are of sufficient width to be provided with holes 10 for receiving the screws, or bolts, or other members which secure the heads of the cylinder to the blocks, and wide enough for seats for gaskets, the block being formed with holes aligned with the holes 10 for receiving the bolts. As shown in Figures 1 and 4, the flanges 9 are rectangular in general form.

However, as seen in Figures 6 and 7, the flanges 11, corresponding to the flanges 9, may be annular and embedded in the body 1 flush with the upper face of the body so that the screws, or bolts,

which secure the heads to the body, thread directly into the head, and not through the flange.

In forming this cylinder block, the sleeves, or liners, are properly set in the mold, and the body of aluminum alloy, or other metal having relatively high heat conductivity, cast around the sleeve. The block is also formed with a suitable base flange 12 by which it is mounted upon the crank case of the engine.

10 One or more of these multi-cylinder blocks may be used in a single engine, either V type, or in-line type, and a cooling air current is blown in a direction lengthwise of the blocks, or the flanges 3, and directed in any suitable manner to pass cross-
15 wise thereof between the blocks.

10 The large mass of metal between the cylinder walls absorbs heat from the cylinder bores and equalizes or tends to equalize the absorption of the heat from portions of the walls between the cylinder bores with the remaining portions of the walls of the cylinders, which are more in the direct path of the air current. The ventilating passage 5 through this intermediate mass of metal between the cylinder bores, tends to equalize the cooling of the intermediate mass between the cylinder bores with the cooling of the outer sides of the mass exposed more directly to the cooling air current, or tends to avoid localizing of the heat in the portion of the mass between the bores.

20 30 This cylinder block is comparable in cost of manufacture to a multi-cylinder block for water cooled engines, and owing to its construction, makes it possible to bring the cost of an efficient air cooled engine to that of a water cooled engine.

35 What I claim is:

1. A multi-cylinder block for air cooled engines comprising a body formed with a plurality of cylinder bores, heat radiating flanges encircling the body with the portions thereof on the sides of the block continuous across the portion of the body between the bores, and with a passage extending lengthwise of the bores in the portion where the bores are closest together, the bores being provided with sleeve liners embedded in the body, said liners being exposed in said passage.

40 45 2. A multi-cylinder block for air cooled engines

comprising a body formed with a plurality of cylinder bores, heat radiating flanges encircling the body with the portions thereof on the sides of the block continuous across the portion of the body between the bores, and with a passage extending lengthwise of the bores in the portion where the bores are closest together, the bores being provided with sleeve liners provided with peripheral flanges embedded in the block, the liners and their flanges being exposed in said passage.

3. A multi-cylinder engine block comprising a body formed with a plurality of cylinder bores, sleeve liners in the bores and having peripheral projections embedded in the body, the body having heat radiating flanges extending around the body and the portions of the flanges on the sides of the block between the bores being continuous of the portions of the flanges around the ends of the block, the body being of a metal having a greater heat conductivity than the liners, the portion of the body between the bores and the liners being formed with a passage extending lengthwise of the bores in which passage the contiguous portion of the liner and projections are exposed whereby localization of heat in the portion of the block between the liners is avoided.

4. A multi-cylinder engine block comprising a body formed with a plurality of cylinder bores, sleeve liners in the bores and having peripheral projections embedded in the body, the body having heat radiating flanges extending around the body, and the portions of the flanges on the sides of the block between the bores being continuous of the portions of the flanges around the ends of the block, the body being of a metal having a greater heat conductivity than the liners, the portion of the body between the bores and the liners being formed with a passage extending lengthwise of the bores, portions of the sleeve liners being exposed in said passage, whereby naked portions of the liners are exposed in said passage and localizing of the heat in the mass between the liners, and hence distortion of the liners, avoided.

CHARLES S. BROWN.

CERTIFICATE OF CORRECTION.

Patent No. 2,012,740.

August 27, 1935.

CHARLES S. BROWN.

It is hereby certified that error appears in the printed specification of the above numbered patent requiring correction as follows: Page 2, first column, after line 29, insert the words By this construction, the cylinder bores of an air cooled block can be located close together, and the cylinders as efficiently cooled as in air cooled engines where individual cylinders are used to provide a cooling air space between them: and that the said Letters Patent should be read with this correction therein that the same may conform to the record of the case in the Patent Office.

Signed and sealed this 8th day of October, A. D. 1935.

Leslie Frazer
